UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

1,416,322.

Specification of Letters Patent. Patented May 16, 1922.

Application filed April 23, 1920. Serial No. 376,126.

To all whom it may concern:

Be it known that I, JOSEPH BECKER, a citizen of the United States, residing in Pittsburgh, in the county of Allegheny and 5 State of Pennsylvania, have invented a new and useful Improvement in Coking Retort Ovens, of which the following is a specification.

This invention comprehends improvements of general utility in the coking retort oven art; and also comprehends certain improvements especially applicable to coking retort ovens of the well known Koppers cross-regenerative type exemplified in the 15 patent to H. Koppers No. 818,033 dated April 17, 1906.

The invention has for one of its objects the provision of a coking retort oven having, as an important characteristic, an extreme flexibility in operation exemplified in 20 the ready adaptability of the oven for operation either with producer gas as a fuel, or with coke-oven gas burned in an atmosphere of ordinary preheated air, such as is utilized in ordinary coke ovens, or with coke oven gas burned in an atmosphere containing both air and a neutral gaseous diluent which is introduced into the combustion flues separately from the air. By the invention, a 25 quick and ready conversion of the oven for operation according to any one of the modes above specified, may be effected without making any special adjustments, other than varying the operation of installed control 30 parts, as will be hereinafter more fully explained.

Also of general application in the coking retort oven art, is a further object of the invention to provide a process and apparatus for increasing the efficiency of coke-oven gas or other gases rich in hydrogen content, when employed as a fuel for effecting the carbonization of the coal, in that an even distribution of the heat over the area 35 of the heating walls is promoted and the harmful effects of flame concentration avoided. This object, in accordance with the present invention is attained without the necessity of making alterations or reconstructing 40 the internal structure of a coking plant that is also adaptable for using as a fuel a special generator gas, such as producer gas.

In addition to the general objects recited above, the invention has for further objects

such other improvements or advantages in 55 construction and operation as are found to obtain in the structures and devices herein-after described or claimed.

In the accompanying drawings, forming a part of this specification, and showing, for 60 purposes of exemplification a preferred form and manner in which the invention may be embodied and practiced, but without limiting the claimed invention specifically to such illustrative instance or instances: 65

Figure 1 is a general view of a small coking plant embodying features above specified and equipped with the improvements of the present invention, the view being taken on vertical planes crosswise of the plant through 70 a coking chamber, the regenerators and other parts;

Fig. 2 is a composite vertical section and elevation of a coking retort oven embodied in a plant of the type illustrated in Fig. 1, 75 the sectional portion of the figure being taken on vertical planes longitudinally of the battery indicated by the lines C—C, D—D, E—E and G—G of Fig. 3;

Fig. 3 is a transverse section taken transversely through a heating wall of the coking retort oven in a plane indicated by the line A—A of Fig. 2;

Fig. 4 is a vertical section taken transversely through a coking chamber of the 85 coking retort oven in a plane indicated by the line B—B of Fig. 2;

Fig. 5 is an enlarged vertical sectional elevation taken transversely through the pusher side of a coking retort oven such as 90 illustrated in Fig. 1 and showing certain fuel and exhaust mains and their controlling connections hereinafter more fully described;

Fig. 6 is an enlarged fragmentary elevation, looking toward the pusher side of the oven and showing partly in section and partly in elevation the devices illustrated in Fig. 5; 95

Fig. 7 is an enlarged fragmentary top plan view of the controlling devices illustrated in Figs. 5 and 6; and

Fig. 8 is a fragmentary horizontal section through the heating walls and coking chambers of the coking retort oven. 100

The same characters of reference indicate the same parts throughout the several views.

In its present embodiment, the invention

is incorporated in a small coking plant, such as is illustrated in the accompanying drawings and having features of the wellknown Koppers cross-regenerative type, exemplified in the patent to H. Koppers hereinabove mentioned, which coking retort oven or plant includes in its construction crosswise-extending parallel heating walls constituted of series of vertical flame or combustion flues, elongated coking chambers or ovens intermediate the heating walls, and parallel therewith, and crosswise extending regenerators located at a lower level than the coking chambers and the heating walls and parallel therewith. For convenience, the present description will be confined to this use of the invention; features of construction and operation are, however, readily susceptible to other valuable applications and consequently, it is manifest that the scope of the invention is by no means confined to the specific use and specific embodiment herein described as an illustrative example.

Referring to the drawings, there are illustrated sectional views of a coke oven battery or plant of the by-product type, such as has been hereinbefore mentioned, which embodies in its construction a plurality of crosswise elongated heating walls 11, 11 and 30 a plurality of intermediate crosswise elongated vertical coking chambers or ovens 12, 12. The heating walls 11 form the side walls of the respective coking chambers 12, as shown more particularly in Figs. 2 and 35 8, and in the present instance are supported by the heavy supporting or pillar walls 13, 13, extending crosswise of the battery and located, as shown in Fig. 2, beneath the respective heating walls 11. These pillar walls 40 collectively form the main support for the entire superstructure of the oven battery and are themselves firmly supported upon a flat mat or platform 14, which constitutes the sub-foundation on which the entire battery rests. The coal to be coked is elevated by means of a conveying apparatus indicated generally at 15 into the coal hoppers 16 which are supported by a superstructure above the top of the battery of ovens 12. 45 Running on a track 17 on the top of the oven battery is a larry car 18 which receives coal from the hopper 16 and charges the several coking chambers or ovens 12 through charging holes 19 located in the top of the oven battery and positioned directly above the ovens or chambers 12, as shown in 55 Figs. 1 and 4. These charging holes 19 are equipped with the usual removable covers, which are removed during charging of the several ovens and placed in position to close the tops of the ovens during the entire coking operation.

Heat for coking the charges of coal in the several ovens or chambers 12 is derived from 60 the heating walls 11, which, as before men-

tioned, extend crosswise of the battery at the sides of the coking chambers. Referring now more particularly to Fig. 8, each heating wall 11 is constituted of two series, 21 and 22, of substantially triangular flame or combustion flues alternately facing oppositely toward the coking chambers contiguous to either side of each such heating wall. Each of such flues, by reason of its triangular form, is relatively narrow transversely 75 of the wall and presents a wide heating face towards the contiguous coking chamber. The said two series of flues in each heating wall are operatively disposed in two groups, each of about half the length of the heating 80 wall and respectively on opposite sides of the center line 23, indicated at about the middle of the length of the heating wall shown in longitudinal section in Fig. 3 and in horizontal section in Fig. 8. 85

The crosswise regenerators 24 of the retort oven or battery are located at a lower level than the aforesaid heating walls 11 and coking chambers 12 and in the present instance extend in parallelism beneath the coking 90 chambers 12 between the pillar walls 13. Below the middle lengthwise line of the heating walls 23 aforesaid, there is a partition 25, as shown in Figs. 1, 3 and 4, which extends all the way up from the mat of the 95 battery to the bottom of the overlying coking chamber and from one to the other of the pillar walls 13, such partition corresponding in position with the line between the hereinbefore mentioned two groups of combustion 100 flues. With this construction, there are thus formed below each coking chamber and crosswise of the battery, two end to end regenerators 24, the meeting ends of which are the partition 25 above mentioned. Each regenerator 24 is a chamber containing open brickwork commonly called checkerwork and indicated at 26, with a distributing sole channel 27 underneath the checkerwork of each regenerator, the channels forming the 105 soles of such chambers and opening up into the checkerwork of their respective regenerators. These regenerators in alternation are heated by the hot combustion products that are exhausted from the flame or combustion 110 flues hereinbefore mentioned and then impart such heat to the medium that they feed into these flame flues, the preheated medium so fed into the flame flues varying in accordance with the character of oven operation, as 115 will hereinafter appear. In accordance with the present embodiment of the invention, the sole channels 27 of the regenerators on both sides of the longitudinal partition wall 23 extend from the same side of the battery to 120 their respective regenerators, and the inflow to or the outflow from the regenerators on both sides of such partition wall 25 is controlled from one side of the battery, preferably although not necessarily the pusher 125 130

side, designated generally by the letter A. It will be noted, by reference to Figs. 2, 3 and 4, that the sole channels 27 are disposed in pairs, one sole channel of each pair opening up into the checkerwork of a regenerator on the near side of the dividing partition 25 and the other sole channel of such pair extending under the aforesaid regenerator and opening up into the checkerwork of the regenerator on the far side of the dividing partition.

The reversal in direction of flow through the several regenerators of the battery, and also through the flame or combustion flues of the heating walls with which the regenerators communicate, takes place crosswise of the battery in accordance with the mode of operation employed in the patent to Koppers above mentioned. For example, all of the regenerators 24 on one side of the partition 25 operate concurrently as inflow regenerators, while all of the regenerators on the opposite side of the partition 25 are operating concurrently as outflow regenerators, and this is true notwithstanding the medium introduced into the several regenerators. On reversal by means of the reversing connections hereinafter described, all of the regenerators on the far side of the aforesaid partition 25 become inflow operating regenerators while at the same time all of the regenerators on the near side of the partition become outflow operating regenerators.

Each flue of both series 21 and 22 of each heating wall has at its top a port or opening 28 for draft and the passage of combustion products or waste gas from the flames within the flues. These ports 28 open up into horizontal flues 29 formed in the heating walls and connecting all the flues of both series and groups of each heating wall together. In the operation of the oven battery, the several flues on one side of the longitudinal dividing line 23 operate as upburning flues while concurrently the several flues on the other side of such dividing line 23 operate as downdraft or exhaust flues, the several flues on each side of such dividing line exchanging functions on reversal of the oven. The horizontal channels or flues 29 just mentioned serve to direct the exhaust gases issuing from the ports 28 of the upburning flues into the similar ports 28 of the downdraft flues on the opposite side of the longitudinal dividing line. The draft through the ports 28 can be regulated by means of the usual movable dampers or sliding bricks, positioned in the ordinary way in the bottoms of the horizontal flues 29 and adapted to be reached by access flues 30 which extend from the top of the channels 29 in each heating wall to the top 15 of the battery, there being an access flue positioned over each flame or combustion flue of each heating wall.

Extending crosswise of the battery in each pillar wall 13 and located beneath the heating wall 11 thereabove, is a pair of gas-supply channels 31 and 32, the channel 31 being located above the channel 32, as shown 70 in Figs. 2 and 3. These channels 31 and 32 are for the purpose of supplying coke oven gas to the several flues on each side of the central dividing line indicated at 23, and to accomplish this end, the channel 31 communicates with the individual flues 21 and 22 disposed in the groups on the near side of the line 23 by means of ducts 33 that lead from such channel 31 individually into the bottoms of individual flues; and the channel 80 32 which supplies the several flues 21 and 22 of the groups of flues on the far side of the dividing line 23 communicates therewith by means of similarly connecting ducts 34. Within the several ducts 33 and 34 are disposed the usual nozzles 35.

The supply of coke oven gas to the channels 31 and 32 of the respective heating walls 11 is derived from a coke oven gas main 36 located in the present instance on the pusher 90 side A of the battery and extending longitudinally therewith, as shown in Fig. 6. Connected with said main 36 is a series of supply pipes 37 respectively leading to branch pipes 38 which terminate respectively 95 in gas guns 39 that enter the inlets of pairs of adjacent gas channels 31, there being a branch pipe 38 and gun 39 for each of such channels. A second series of supply pipes 40 also connects with the supply main 36 and 100 each supply pipe 40 is provided with branches 41 having at their discharge ends guns 42 that respectively enter the inlets of a pair of channels 32 fed by each supply pipe 40. The several supply pipes of the 105 series 37 are individually provided with controlling valves 43 operable by valve operating levers 44, all of which levers are controlled by a single cable 45. Similarly the supply pipes of the series 40 are provided 110 with controlling valves 46 respectively operable by valve operating levers 47 all of which are controlled by a single cable 48, as shown in Fig. 5. These cables 45 and 48 are controlled from a central reversing station and 115 assuming that the oven is operating with coke oven gas as a fuel, the cables 45 and 48 are operated at each periodic reversal of the battery to admit gas to one series of gas channels, 31 or 32, and turn off the gas from 120 the other, the channels 31 receiving a supply of gas from the main 36 while the channels 32 are shut off from such main and vice versa, in accordance with the reversal in direction of flow through the flues 21 and 22, 125 as hereinbefore explained.

The ducts by which the several regenerators communicate with the flues of the series 21 and 22 are in their general arrangement similar to those disclosed in my prior 130

Patent No. 1,312,301 dated August 5, 1919 and the prior patent to Joseph van Ackeren No. 1,312,372 dated August 5, 1919. Each regenerator communicates with each flue of both series of flues in each of the two heating walls adjacent opposite sides of the top of such regenerator, extending substantially half the length of the coking chamber above said regenerator. Such communication between the flues and regenerators is by means of forked regenerator ducts 49, each extending (as fully disclosed in the said two patents and as shown in Fig. 2) first obliquely and then vertically up into the heavy pillar wall 13, and then forking into two ascending ports 50, 51 that respectively open into a pair of oppositely facing contiguous flues, one in each of the two flue series in the heating wall. These two branches of such forked duct become substantially vertical under the flue into which each becomes a port, and are so offset from the main channel of the duct (at its place of forking F) as to equalize the regenerator flow from such channel into and through such branches of the fork.

Referring now more particularly to Figs. 6 and 7, the sole channels 27 of each pair of regenerators positioned endwise beneath a coking chamber respectively communicate with air boxes located, according to the present embodiment of the invention, on the pusher side of the oven battery. That is to say, the sole channel 27 of each regenerator on the near side of the longitudinal partition 25 communicates with an air box 52; and each regenerator on the far side of the aforesaid longitudinal partition communicates with an air box 53; this results in the arrangement of two series of air boxes 52 and 53 along the pusher side of the oven battery, the air boxes of each series being in communication with regenerators located as aforesaid. Extending longitudinally of the battery or plant is an exhaust main 54 for the waste gases or products of combustion exhausted from the several regenerators (see Figs. 3 and 4) and each air box of both series 52 and 53 is provided with a port 55 leading to a channel 56 which opens up into the aforesaid exhaust main 54. The several air boxes of both series are respectively provided with dampers 57 for opening and closing the ports 55 with respect to the exhaust main 54 and these dampers 57 are adapted to be operated by damper-operating levers 58. All of the damper-operating levers 58 of the series of air boxes 52 are controlled and operated by a single cable 59 and similarly all the damper-operating levers 58 of the series of air boxes 53 are controlled and operated by a single cable 60, as shown more particularly in Fig. 7. Accordingly by operation (controlled at the central reversing station hereinbefore mentioned) of the two damper-controlling cables 59 and 60

during the reversal period hereinbefore mentioned, the several regenerators on one side of the longitudinal partition 25 are shut off from communication with the exhaust main.

The several air boxes of both series 52 and 53 are furthermore provided with lids 61 for opening and closing the interior of the respective air boxes to the outer air according to the mode of operation of the coking plant, as will hereinafter appear. Each air box lid 61 is adapted to be operated by a lid-operating lever 62 and the levers 62 of alternate pairs of air boxes 52 and 53 are controlled and operated by a single cable 63, whereas the levers 62 of the pairs of air boxes 52 and 53 intermediate such alternate pairs of air boxes aforesaid are controlled and operated by a single cable 64, as shown more particularly in Figs. 6 and 7. The cables 63 and 64 are respectively provided with stops 65 and 66 suitably positioned therealong for engaging and operating the several levers which they control, such stops being adapted on movement of the cables in one direction to engage certain of the levers 62 and operate them, while concurrently releasing other levers 62 permitting the corresponding lids 61 to remain in or be returned to closed position. Both the cables 63 and 64 are movable into three positions, that is into neutral, right, and left positions. When either of the cables 63 or 64 are in neutral position, the lids 61 of all of the alternate members of both series 52 and 53 of air boxes that such cables control are in closed position. The operation of one of the cables to its left position, for example the cable 64 as indicated in Fig. 6, results in the opening of the lids 61 of one member of each alternate pair of air boxes, such as the lids of the air boxes 52 that are controlled by the cable 64 aforesaid, whereas the lids of the air boxes 53 of the same alternate pairs of air boxes remain in closed position. Conversely, on movement of the same operating cable 64 toward the right, the lids of such air boxes 53 as it controls are opened and the previously opened lids of the air boxes 52 are permitted to close. The other cable 63 controls the pairs of air boxes intermediate the alternate pairs controlled by the cable 64, in exactly the same manner as has just been described. Consequently, by operating both cables simultaneously in the same direction all of the air boxes of either series 52 or 53 may be opened, this depending on whether the cables are moved to the right or left positions. In so operating the cables, the lids of an entire series of air boxes 52 may be opened while the lids of an entire series of air boxes 53 are closed. Either cable, however, may be operated independently of the other and as each cable controls only alternate pairs of air boxes the operation of one cable to right and left position, while the

other cable remains in neutral position would result in opening the lid 61 of only every fourth air box while the lids of all the other air boxes remain in closed position. 5 The operating connections for the air boxes are thus capable of great flexibility of control, all of which is taken advantage of in the conversion of the oven operation into one of the several modes of operation, as herein- 10 before mentioned and to be set forth presently in detail.

The exhaust main or waste gas tunnel 54 leads to and is adapted to conduct the waste gases from the downflow flues and outflow 15 regenerators to the usual waste gas stack, not illustrated, but of any approved construction. Extending longitudinally along the pusher side of the battery or plant is a return waste gas or exhaust supply main 67, 20 which is supplied with waste gas or products of combustion that are discharged into the waste gas tunnel 54. Suitable connections may be provided for leading a portion of the waste gas from the tunnel 54 into the 25 waste gas supply main 67, these being preferably located at or in the vicinity of the stack. It is furthermore preferable to pass the waste gas from the tunnel 54 through a cooler of any approved construction before 30 feeding such gas into the waste gas supply main 67, as the gas in the tunnel 54 is still too hot, in most cases, for being fed back through the supply main 67 and subsequently into valve control connections leading 35 from said main 67. The supply of waste gas to the main 67 may be opened up or shut off at will at the point where the main 67 is connected with the tunnel 54 by means of a suitable controlling valve. Alongside of the 40 waste gas supply main 67 is a producer gas supply main 68 leading from a suitable source of supply of producer gas and also adapted to be opened up to or shut off from its source of supply by means of an approved 45 controlling valve. The valves that control the supply to the waste gas main 67 and producer gas main 68 are not herein illustrated for the reason that the specific construction of such valves is wholly immaterial to the present invention.

Leading into each air box of both series of air boxes 52 and 53 is a branch supply pipe 69 and such pipes 69 are severally connected with the aforesaid waste gas supply 55 main 67 by means of vertical branches 70, shown more particularly in Fig. 5. Each branch 70 is provided with its individual valve 71, permitting individual control of the flow from the main 67 into the several 60 branch pipes 69. These branch pipes 69 are respectively provided with cable-operated valves 72 having valve-operating levers 73, as shown in Figs. 5, 6 and 7. According to the present arrangement, the pairs of valves 65 72 corresponding to alternate pairs of air

boxes 52 and 53 are opened when their valve operating levers 73 are moved in one direction; whereas the pairs of valves 72 corresponding to the pairs of air boxes 52 and 53 that are intermediate the alternate pairs of air boxes aforesaid are opened only when their valve operating levers 73 are moved in the opposite direction. All of the valve operating levers 73 that control the flow in the branches 69 leading into the entire series 75 of air boxes 52 are operated by a single cable 74 and similarly all the valve operating levers 73 that control the flow into the air boxes of the entire series 53 are operated by a single cable 75. The caps 74 and 75 are 80 also controlled from the above-mentioned central reversing station. Connected with the branch pipes 69 of alternate pairs of air boxes 52, 53 as shown in Fig. 7, are producer gas supply pipes 76 which are individually 85 connected with the producer gas main 68 by means of vertical pipes 77. The vertical pipes 77 are also provided with individual valves 78 for controlling the flow of producer gas into the branch pipes 69, with 90 which such vertical pipes 77 are connected.

As hereinbefore stated, one of the essential features of the invention is the attainment of an extreme flexibility in operation of a coking plant, permitting a ready adaptability of the oven for operation either with producer gas as a fuel or with coke oven gas burned in an atmosphere of ordinary pre-heated air such as is utilized in ordinary coke ovens, or with coke oven gas burned in an atmosphere containing both air and a neutral gaseous diluent, which is introduced into the combustion flues separately from the air. These ends are attained by the incorporation in a coking plant of structural features and a flexible system of control, such as has been described in connection with the present embodiment of the invention. A number of important advantages and improvements made by the invention can, however, best be pointed out by tracing out separately the operation of the invention, as exemplified in the accompanying drawings, according to its several different modes of operation.

The operation of the retort oven or battery, when using a special generator gas, such as ordinary producer gas, as a fuel is as follows. The return waste gas main 67 is cut off from its source of supply of waste gas by a proper operation of the main controlling valve of said main; the supply of coke oven gas to the coke oven gas main 36 is also shut off; the result is that both the return waste gas main 67 and the coke oven gas main 36 bear an inoperative relation to the oven, in so far as producer gas operation is concerned. A supply of producer gas is however turned on into the producer gas main 68 by opening the main valve of such 130

producer gas main and the producer gas enters the vertical pipes 77 and passes into the branch pipes 69 to alternate pairs of air boxes 52 and 53, from which branches the gas may flow in proper sequence into the regenerators 24 that operate to preheat the producer gas before delivering it into the combustion flues. Assuming that the several regenerators arranged on the near or pusher side A of the longitudinal partition wall 25 of the coke oven battery are operating as inflow regenerators and that the several regenerators on the far side or coke side B of the longitudinal partition 25 are operating as outflow regenerators, it follows that the flues 21 and 22 on the pusher side of the longitudinal partition are concurrently operating as upburning flues while the flues on the far side of the longitudinal partition are operating as downflow waste gas flues and are delivering the waste gas or products of combustion into the outflow regenerators through the system of ducts hereinabove specified. On the pusher side of the battery, regenerators through which an inflow of producer gas is maintained alternate with regenerators through which an inflow of outside air is maintained, and by means of the flue and duct construction previously described, every flue receives through its bottom ports 50 and 51 a supply of preheated air from one port and a supply of preheated producer gas from another port, the supply of gas and air being in about equal proportions which are the proper proportions when operating with producer gas. During the period within which the regenerators and flues on the pusher side A of the oven battery are all operating for upflow, the several control devices assume relative positions as follows. The air box lid controlling cable 63 that controls the alternate pairs of air boxes 52 and 53 which are connected with the producer gas main 68 by means of the aforesaid pipes 76 and 77 is maintained constantly in neutral position, notwithstanding subsequent reversal of the upflow from the pusher side of the battery to the coke side of the battery, and consequently the air box lids 61 of these alternate pairs of air boxes 52, 53 always remain closed whenever the oven is operated with producer gas as a fuel. On the other hand however, the other air box lid controlling cable 64 controls only the air box lids of the pairs of air boxes 52 and 53 which are intermediate the pairs of air boxes aforesaid and are not connected with the producer gas main 67, and consequently the cable 64 is operated toward the right or toward the left, at each periodic reversal of the battery to open the air box lids 61 of the inflow operating regenerators on one side of the battery that supply the air and simultaneously to close the air box lids of the outflow regenerators on the opposite side of the

battery. At this time the cable 74 controlling the several valves 72 in the pipes 69 connected with the series of air boxes 52 has been moved to a position to open the valves 72 of the pipes 69 which are connected with the producer gas feed pipe 76, causing a flow of producer gas into alternate regenerators on the pusher side of the battery; the valve operating levers 73 of the valves 72 in the pipe 69 of the intermediate air boxes 52 which are feeding air into the regenerators intermediate the producer gas regenerators do not, according to the arrangement above described, open on movement of the cable 74 in a direction to cause the feed of producer gas into the alternate air boxes 52 aforesaid, and hence there is no interference with the flow of air into the air boxes and thence into the air regenerators. The cable 59 controlling the damper operating levers 58 has been moved to a position to open the dampers 57 of the entire series of air boxes 53, permitting the waste gas that enters such air boxes from the regenerators on the coke side of the longitudinal partition 25 to pass through such air boxes 53 into the waste gas tunnel 54. Simultaneously the cable 60 is maintained in such position as to close the dampers 57 of the entire series of air boxes 52. The positions of the pairs are exactly reversed when the inflow is shifted to the coke side of the battery and the outflow concurrently shifted to the pusher side of the battery, this taking place at the end of one of the usual periodic reversals of the oven. The cable 64 is operated to the reverse position to open the alternate air boxes 53 on the coke side of the battery and close the alternate air boxes 52 on the pusher side of the battery; the cable 60 is operated to close the dampers 57 of the entire series of air boxes 53 and the cable 59 is operated to open the dampers of the entire series of air boxes 52; the cable 74 is operated to close the valves 72 that heretofore permitted producer gas to flow into alternate air boxes 52 connected with alternate regenerators on the pusher side of the battery, while the cable 75 is operated to open the valves 72 of alternate air boxes 53 that are connected with alternate regenerators on the coke side of the battery. As a result of the arrangement of the cable 75 and valves 72 that are disconnected, the movement of the cable to open the valves 72 which are connected with the producer gas regenerators on the coke side of the battery does not open the valves 72 of the pipe 69 leading to the air boxes 53 which are connected to the air regenerators on the coke side of the battery, such air regenerators being free to draw in air through the air ports of their respective air boxes 53.

In operating the oven with coke oven gas in the ordinary manner, both the producer gas in the main 68 and the waste gas in the main

67 is shut off and at the same time both cables 74 and 75 are operated to positions to close the entire series of valves 72. On reversal of the oven from the pusher side to coke side and vice versa both air box lid controlling cables 63 and 64 are operated simultaneously in the same direction to open either the entire series of air boxes 52 to the outer air or vice versa to open the entire series of air boxes 53 to the outer air, this depending on whether the inflow is maintained through the regenerators on the coke or pusher side of the oven. The cables 59 and 60 are operated in alternation at the end of each reversal period to connect over the entire series of air boxes 52 with the waste gas tunnel or the entire series of air boxes 53 with said tunnel. When operating according to this manner all of the regenerators on one side of the battery operate as air regenerators, while all of the regenerators on the other side of the battery operate in the usual way as outflow regenerators. On reversal the outflow regenerators become air regenerators and the air regenerators become outflow regenerators. The coke oven gas is turned on to the coke oven gas main 36 and the cables 45 and 48 controlling the feed of the coke oven gas through the gas guns 39 and 42 are operated in alternation to supply coke oven gas to the upburning flues and concurrently cut off the supply of coke oven gas from the downburning flues.

The invention embodies a further mode of operation in that coke oven gas may be used as a fuel, while simultaneously there is maintained to the upburning flues a supply of a neutral gaseous diluent, the neutral gaseous diluent entering the flues independently of both the coke oven gas and the air and performing the important function of greatly lengthening the flame, so as to equalize temperature conditions throughout a maximum area of the heating wall and prevent intense heat concentration in the lower portions of the walls. By this, a long flame is obtained, approximating that obtained when employing, as fuel, an extraneously-derived gas, such as producer gas. To this is added the further feature that the neutral gaseous diluent, which is supplied to alternate regenerators connected with the upburning flues through the system of ducts above specified, may be switched at will to the regenerators intermediate such alternate regenerators. This switching of the flow of neutral gaseous diluent from alternate regenerators to regenerators intermediate such alternate regenerators may take place at will at the end of each periodic reversal of the oven or may be effected only at the end of occasional reversal periods. The possibility of switching the flow of neutral gaseous diluent from certain regenerators to others greatly increases the flexibility of the

oven as a whole and is an important factor in maintaining a heat balance throughout the entire battery.

The following is the mode of operation when the oven battery burns coke oven gas 70 as a fuel, combined with a supply of neutral gaseous diluent to the upburning flues. The supply of producer gas to the producer gas main 68 is turned off and the supply of coke oven gas to the coke oven gas main 36 is 75 turned on. The reversal of coke oven gas to the flues on the opposite sides of the longitudinal partition 25 is effected in the same manner as in the ordinary coke oven gas operation just described. By operating the 80 main controlling valve of the return waste gas main 67 a supply of cooled waste gas is permitted to flow from the waste gas tunnel 54 into said main 67. When one series of regenerators operate as air regenerators 85 and the regenerators intermediate such air regenerators operate as return waste gas regenerators for supplying the neutral gaseous diluent to the flues, the air box lid controlling cable 64 remains in neutral position, while the lid cable 63 is operated at the end of each periodic reversal of the oven to alternately open and close the lids 61 of the intermediate air boxes 52 and 53 such air boxes supplying air in alternation 90 to the intermediate air regenerators on the opposite sides of the battery. The cables 59 and 60 are obviously operated in the same way as has been heretofore described. While the air boxes controlled by the cable 63 10 are active for supplying air in alternation, the intermediate pairs of air boxes 52, 53 are utilized to supply the gaseous diluent, or waste gas in alternation to the alternate waste gas regenerators on the opposite sides 10 of the battery. The two cables 74 and 75 are thus operated in alternation in the same direction to connect either the alternate air boxes 52 with the waste gas main or the alternate air boxes of the series 53, this 110 depending on whether the flow is maintained through the waste gas regenerators on the coke or pusher side of the battery. During the entire time that the oven is operating in this manner the valves 72 connected with the air boxes that supply air remain constantly closed. When it is desired to switch the air regenerators with the waste gas regenerators, at the end of any period of reversal of the battery, the 115 cable 63 is restored to neutral position and the cable 64 is operated in alternation to supply air to the air boxes 52 and 53 which it controls. The two cables 74 and 75 controlling the valves 72 are operated in a direction reversely from that previously described and as a consequence the valves 72 that heretofore remained closed are opened, in alternation, this depending on which 120 cable 74 or 75 is operated in the reverse direction. The valves 72 that have been opened 125 remain open until the end of the reversal period, at which time the cable 63 is restored to neutral position and the cable 64 is operated in alternation to supply air to the air boxes 52 and 53 which it controls. The two cables 74 and 75 controlling the valves 72 are operated in a direction reversely from that previously described and as a consequence the valves 72 that heretofore remained closed are opened, in alternation, this depending on which 130 cable 74 or 75 is operated in the reverse direction.

tion. The valves 72 that are intermediate the valves now opened in alternation remain closed on reverse movement of either cable and no waste gas is permitted to enter the regenerators which have been switched from waste gas regenerators to air regenerators.

On the pusher side A of the battery, there is provided a pusher machine 79 of any preferred construction, which pusher machine operates in the usual way to push the charges of finished coke from the coking chambers 12 at the ends of the coking periods in such chambers.

In the present embodiment of the invention, the finished coke falls through the coking-chamber opening on the coke side of the battery and on an inclined coke wharf 80 that extends downwardly from approximately the floor level of the several coking chambers. The hot coke is quenched on this wharf by water supplied from a hose 81 connected with any suitable source of water supply. At the lower end of the coke quenching and discharge wharf or chute 80 is an endless conveyer 81 which is adapted to carry away the freshly quenched coke for the usual subsequent handling. Before and during the quenching operation the coke is prevented from falling on to the upper run of the conveyer by means of a pivoted gate 82 which is adapted to close the lower end of the aforesaid wharf or chute 80. The gate 82 is provided with an operating lever 83 permitting it to be opened and closed as required. Beneath the gate 82 is a deflecting apron 84 pivoted at 85. When the gate is opened apron 84 may be swung into the position indicated by dotted lines in Fig. 1 so that it acts as a guide for directing the coke from the lower end of the chute 80 to the conveyer 81. When the gate is closed, the apron 84 is swung to the position indicated by full lines in said figure, to act as a guide for directing the water that discharges off the lower end of the chute 80 into a discharge trough 86 located beneath the lower end of said chute.

The side walls of the battery are braced by pairs of buckstays 87 extending from the top of the battery down in front of the pillar walls. The gases of distillation discharge from the tops of the several coking chambers 12 into ascension pipes 88 from which they pass to a collecting main 89, which carries the gases to the usual by-product recovery apparatus.

The invention as hereinabove set forth is embodied in a particular form of construction but may be variously embodied within the scope of the claims hereinafter made.

The features relating to the coke quenching and handling apparatus shown or described in the foregoing specification are

made the subject matter of my divisional application for Letters Patent of the United States executed April 14, 1922, filed April 18, 1922, for coke handling apparatus and no claim to such coke quenching and handling apparatus is made in the present application.

I claim:

1. In a coking retort oven, in combination: a plurality of coking chambers; heating walls contiguous to such coking chambers and respectively constituted of two series of substantially triangular combustion flues arranged on opposite sides of the heating walls; regenerators disposed in in-flow and out-flow groups and located at a lower level than the coking chambers and the heating walls and parallel therewith, the regenerators being arranged in pairs and one regenerator of each pair being positioned end to end with the other regenerator of that pair; a system of ducts connecting the regenerators on each side of the oven with the flues on the same side of the oven; a coke oven gas-supply combined with means for alternately feeding the coke oven gas to the flues on the opposite side of the oven; a waste gas supply; means for feeding waste gas to alternate in-flow regenerators and for concurrently permitting the flow of air through in-flow regenerators intermediate such alternate regenerators; and means for effecting interchange of the feed of air and waste gas to such inflow regenerators; substantially as specified.

2. In a coking retort oven, in combination: a plurality of coking chambers; heating walls contiguous to such coking chambers and respectively constituted of two series of combustion flues arranged on opposite sides of the heating walls; regenerators disposed in in-flow and out-flow groups and located at a lower level than the coking chambers and the heating walls and parallel therewith, the regenerators being arranged in pairs and one regenerator of each pair being positioned end to end with the other regenerator of that pair; a system of ducts connecting the regenerators on each side of the oven with the flues on the same sides of the oven; a coke oven gas supply combined with means for alternately feeding the coke oven gas to the flues on the opposite sides of the oven; a waste gas supply; means for feeding waste gas to alternate in-flow regenerators and for concurrently permitting the flow of air through in-flow regenerators intermediate such alternate regenerators; and means for effecting interchange of the feed of air and waste gas to such inflow regenerators; substantially as specified.

3. In a coking retort oven, in combination: a plurality of coking chambers; heating walls contiguous to such coking chambers and respectively constituted of two series of

combustion flues arranged on opposite sides of the heating walls; regenerators disposed in in-flow and out-flow groups and located at a lower level than the coking chambers and the heating walls and parallel therewith; a system of ducts connecting the regenerators on each side of the oven with the flues on the same sides of the oven; a coke oven gas supply combined with means for alternately feeding the coke oven gas to the flues on the opposite sides of the oven; a waste gas supply; means for feeding waste gas to alternate in-flow regenerators and for concurrently permitting the flow of air through in-flow regenerators intermediate such alternate regenerators; and means for effecting interchange of the feed of air and waste gas to such in-flow regenerators; substantially as specified.

4. In a coking retort oven, in combination: a plurality of coking chambers; heating walls contiguous to such coking chambers and respectively constituted of vertical combustion flues; regenerators disposed in in-flow and out-flow groups and located at a lower level than the coking chambers and the heating walls and parallel therewith, the regenerators being arranged in pairs and one regenerator of each pair being positioned end to end with the other regenerator of that pair; a system of ducts connecting the regenerators on each side of the oven with the flues on the same sides of the oven; a coke oven gas supply combined with means for alternately feeding the coke oven gas to the flues on the opposite sides of the oven; a waste gas supply; means for feeding waste gas to alternate in-flow regenerators and for concurrently permitting the flow of air through in-flow regenerators intermediate such alternate regenerators; and means for effecting interchange of the feed of air and waste gas to such in-flow regenerators; substantially as specified.

5. A coking retort oven having coking chambers, heating walls contiguous to such coking chambers, and regenerators disposed in in-flow and out-flow groups and communicably connected with said heating walls, combined with means for optionally supplying coke oven gas to said heating walls, and means for optionally permitting the flow of neutral gaseous diluent of an extraneously-derived fuel gas to alternate in-flow regenerators and for concurrently permitting the flow of air to in-flow regenerators intermediate such alternate regenerators; substantially as specified.

6. In a coking retort oven, in combination: a plurality of coking chambers; heating walls contiguous to such coking chambers and respectively constituted of combustion flues; regenerators disposed in in-flow and out-flow groups and communicably connected with said combustion flues; means for feeding a neutral gaseous diluent to alternate in-flow regenerators and for concurrently permitting the flow of air through in-flow regenerators intermediate such alternate regenerators and means for effecting interchange of the feed of air and diluent to such inflow regenerators; substantially as specified.

7. In a coking retort oven, in combination: a plurality of coking chambers; heating walls contiguous to such coking chambers and respectively constituted of combustion flues; regenerators disposed in in-flow and out-flow groups and communicably connected with said combustion flues; a waste gas supply; means for feeding waste gas to alternate in-flow regenerators and for concurrently permitting the flow of air through in-flow regenerators intermediate such alternate regenerators; and means for effecting interchange of the feed of air and waste gas to such in-flow regenerators; substantially as specified.

8. A coking retort oven having coking chambers, heating walls contiguous to such coking chambers, and regenerators disposed in in-flow and out-flow groups and communicably connected with said heating walls, combined with means for permitting the supply of coke oven gas to said walls, means for permitting the flow of waste gas to alternate in-flow regenerators and for concurrently permitting the flow of air to in-flow regenerators intermediate such alternate regenerators, and means, operable at will, for effecting interchange of the flow of air and waste gas to such in-flow regenerators; substantially as specified.

9. In a coking retort oven, in combination: a plurality of coking chambers; heating walls contiguous to such coking chambers and respectively constituted of combustion flues; regenerators disposed in in-flow and out-flow groups and located at a lower level than the coking chambers and the heating walls, the regenerators being connected by ducts with said flues; a coke oven gas supply combined with means for feeding the coke oven gas at will to the flues; means for reversing the direction of flow through said regenerators and flues; a waste gas supply; a producer gas supply; and means for alternatively feeding waste gas or producer gas to alternate in-flow regenerators and for concurrently feeding air to in-flow regenerators intermediate such alternate regenerators, or for feeding air to all of the in-flow operating regenerators; substantially as specified.

10. In a process for controlling combustion in coking ovens, the conducting of the combustion with their own gases of distillation and air and such a proportionate admixture of a neutral gaseous diluent, introduced into the combustion zone independ-

- ently of such gas and air, as to produce heating conditions and effects substantially equivalent to those obtainable in firing such ovens with an extraneously derived gas, such as producer gas; substantially as specified.
11. In a process for controlling combustion in coking ovens, the conducting of the combustion alternatively with their own gas of distillation or with an extraneously derived fuel gas, such as producer gas, and in each instance with air to support the combustion, and in the former instance with such a proportionate admixture of a neutral gaseous diluent, introduced into the combustion zone independently of the air and the fuel gas, as to produce heating conditions and effects substantially equivalent to those obtained in the firing of the other alternatively employed fuel gas; substantially as specified.
12. Means for controlling the combustion in coke ovens comprising, in combination: a combustion chamber provided with an air inlet and a fuel gas inlet, means for introducing air and fuel gas respectively through said inlets into the combustion chamber, and means for introducing into the combustion chamber, independently of the gas and air, a gas having a low oxygen content; substantially as specified.
13. Means for controlling the combustion in coke ovens comprising, in combination: a combustion chamber provided with an air inlet and a fuel gas inlet, means for introducing air and fuel gas respectively through said inlets into the combustion chamber, and means for introducing into the combustion chamber, independently of the gas and air, a neutral gaseous diluent; substantially as specified.
14. In a coking oven, in combination: coking chambers; combustion flues; a fuel gas supply adapted to supply to said flues gas of distillation from the coking chambers; an air supply to said flues; and means for supplying also to said flues and independently of the air and gas such a proportionate admixture of a neutral gaseous diluent as to produce heating conditions and effects substantially equivalent to those obtainable in firing such ovens with an extraneously derived gas, such as producer gas; substantially as specified.
15. In a coke oven, in combination: coking chambers; combustion flues; a fuel gas supply adapted to supply to such flues gas of distillation from the coking chambers; an alternative fuel gas supply adapted to supply to said flues an extraneously derived gas; such as producer gas; means for alternatively admitting and shutting off such fuel gas supplies; and means for supplying also to said flues, when said first named fuel gas is employed and independently of the gas and air, such a proportionate admixture of a neutral gaseous diluent as to produce heating conditions and effects substantially equivalent to those obtainable in firing of other alternatively employed fuel gases; substantially as specified.
16. In a coke oven battery, in combination; a plurality of coking chambers; heating walls contiguous to such coking chambers; cross-wise regenerators disposed in series on both sides of the battery and communicably connected with said heating walls; and flow-reversing devices disposed only on one side of the battery for reversing the direction of flow through the series of regenerators on both sides of the battery; substantially as specified.
17. In a coke oven battery, in combination; a plurality of coking chambers; cross-wise regenerators disposed at a lower level than said coking chambers and in two series and communicably connected with said heating walls; and flow-reversing devices disposed only on one side of the battery for reversing the direction of flow through both series of said regenerators; substantially as specified.
18. In a coke oven battery, in combination; a plurality of coking chambers; heating walls contiguous to such coking chambers; cross-wise regenerators disposed in series on both sides of the battery and communicably connected with both said heating walls; fuel gas supply means located on one side of the battery; and flow-reversing devices disposed only on the same side of the battery as said fuel gas supply means, said flow reversing devices operating periodically to reverse the direction of flow through the series of regenerators on both sides of the battery and to control the feed of fuel gas from said supply means whereby fuel gas is fed only to that portion of the heating walls that is communicably connected with regenerators that are operating for in-flow; substantially as specified.
19. In a coke oven battery, in combination; a plurality of coking chambers; heating walls contiguous to such coking chambers and respectively constituted of combustion flues; regenerators disposed in series on both sides of the battery; ducts connecting the respective regenerators with the flues; a fuel gas supply means combined with periodically-operable, flow-reversing devices for alternately feeding the fuel gas to the flues on the opposite sides of the battery; and periodically-operable, flow-reversing devices located on the same side of the battery as the aforesaid gas-flow-reversing devices, for reversing the direction of flow through the regenerators on both sides of the battery; substantially as specified.
20. In a coke oven battery, in combina-

- tion; a plurality of coking chambers; heating walls contiguous to such coking chambers and respectively constituted of combustion flues; regenerators disposed in series 5 on both sides of the battery and communicably connected with said combustion flues; a coke oven gas-supply means combined with periodically-operable, flow-reversing devices for alternately feeding the coke oven gas to 10 the flues on the opposite sides of the battery, and periodically-operable flow-reversing devices, located on the same side of the battery as the aforesaid gas-flow-reversing devices, for reversing the direction of flow through 15 the regenerators on both sides of the battery; substantially as specified.
21. A coking retort oven having coking chambers, heating walls contiguous to such coking chambers, and regenerators disposed 20 in in-flow and out-flow groups and communicably connected with said heating walls, combined with means for permitting the flow of a neutral gaseous diluent to some of the in-flow regenerators and for permitting 25 the flow of air to others of the in-flow regenerators and means for optionally effecting an interchange of the flow of air and neutral gaseous diluent to such in-flow regenerators, substantially as specified.
- 30 22. A coking retort oven having coking chambers, heating walls contiguous to such coking chambers, and regenerators disposed in in-flow and out-flow groups and communicably connected with said heating walls, 5 combined with means for operating some of the in-flow regenerators substantially for the flow of a neutral gaseous diluent and for operating others of the in-flow regenerators
- substantially for the flow of air; substantially as specified. 40
23. A coking retort oven having coking chambers, heating walls contiguous to such coking chambers, and regenerators disposed in in-flow and out-flow groups and communicably connected with said heating walls. 45 combined with means for effecting the operation of said in-flow regenerators conjointly as air regenerators or separately as air and return waste gas regenerators; substantially as specified. 50
24. A coking retort oven having coking chambers, heating walls contiguous to such coking chambers, and regenerators disposed in in-flow and out-flow groups and communicably connected with said heating walls, 55 combined with a return waste gas main receiving waste gas from the out-flow regenerators, and means for effecting communication between said return waste gas main and some of the in-flow regenerators; substantially as specified.
25. A coking retort oven having coking chambers, heating walls contiguous to such coking chambers, and regenerators disposed in in-flow and out-flow groups and communicably connected with said heating walls, 60 combined with a return waste gas main receiving waste gas from the out-flow regenerators, and flow-controlling devices directly connecting said return waste gas main with the in-flow regenerators, whereby return waste gas may be optionally directed into some of the in-flow regenerators; substantially as specified. 65

JOSEPH BECKER.
